 HIS ATTORNEY

UNITED STATES PATENT OFFICE.

ARTHUR W. SMITH, OF NEW YORK, N. Y., ASSIGNOR, BY MESNE ASSIGNMENTS, TO REMINGTON TYPEWRITER COMPANY, OF ILION, NEW YORK, A CORPORATION OF NEW YORK.

TYPE-WRITING MACHINE.

1,132,743.

Specification of Letters Patent. Patented Mar. 23, 1915.

Application filed January 18, 1913. Serial No. 742,801.

To all whom it may concern:

Be it known that I, ARTHUR W. SMITH, citizen of the United States, and resident of the borough of Manhattan, city of New York, in the county of New York and State of New York, have invented certain new and useful Improvements in Type-Writing Machines, of which the following is a specification.

10 My invention relates to severing devices for typewriting machines and its main object is to provide improved devices of the character specified.

More specifically stated, the object of my 15 invention is to provide a severing device for cutting at intervals continuous sheets or strips, such as tally strips, which it has been difficult heretofore to cut cleanly and effectively, the ordinary cutting blade or edge 20 soon becoming dull through use and resulting in a ragged or defective cutting of the paper.

To the above and other ends my invention consists in the features of construction, combinations of devices and arrangements of parts hereinafter described and particularly pointed out in the claims.

In carrying out my present invention I arrange for cutting the sheet by a shearing 30 cut, providing for this purpose two co-operating members or devices, one in the form of a slotted bar or plate and the other of a cutter or blade adapted to work transversely in this slot, the blade co-operating with the 35 face of the bar and the edges of the slot to shear the paper. Normally the face of the slotted bar and the cutting edge of the blade are separated to provide a passage-way or opening through which the paper or 40 work sheet passes, the blade being hinged at one end and provided with a finger piece at the opposite end, the construction enabling the blade to be swung against the paper and drawn through the slot in the bar to 45 sever the paper. The bar remains stationary during the severing operation but is itself hinged or pivoted at the end opposite from the pivot of the blade and provided at its opposite end with a finger piece and a 50 holding device which normally retains it in fixed position on its support. This hinging of the slotted bar is for the purpose of facilitating the introduction of the paper into

the opening or slot between said bar and 55 the cutting blade.

My invention will be explained in detail in connection with the accompanying drawing, wherein—

Figure 1 is a fragmentary front elevation 60 of a platen and platen carrier having my invention applied thereto; and Fig. 2 is a top plan view of the same.

As will be understood from the drawing, the platen carrier comprises a pair of parallel end bars 1, the right-hand bar only being illustrated, and connecting cross-bars 2 and 3. Said platen carrier provides a support for the axle 4 of a rotary platen which may comprise co-axial sections 5 and 6, of which the right-hand section may be employed as a tally platen, being provided with feeding devices or rolls 7 and 8 for facilitating the feeding of work sheets, such, for example, as the narrow sheet or paper herein illustrated at 9 and which may be a tally strip. This tally strip is a long continuous sheet or ribbon and after being advanced upward at the front side of the platen, may be received on a holding device or roller 10 which is pivotally supported on a frame comprising end plates 11 rigidly connected as by a cross bar 12, said end plates being suitably secured to the cross rod or bar 3.

85 The novel severing device to which my invention primarily relates comprises a cutting blade or member 13 and a slotted bar or member 14 with which said blade co-operates. Said blade and said bar are 90 mounted for relative movement, each being pivotally supported on the frame 11, 12, the pivots being at opposite ends from each other, so that such relative movement may be obtained by moving one member or 95 the other. The pivot for the cutting blade is a screw pivot 15 secured in the left-hand plate 11. The body portion of the blade extends horizontally substantially lengthwise of the platen above the rod 3 but its left-hand end portion 16 is offset forward and slightly toward the left, being formed with a hole which receives the shank of the screw pivot 15. A restoring spring 17 is coiled around the screw 15 and has one end 100 anchored to the end plate 11, the opposite end being hooked around the off-set 16.

Said spring tends constantly to swing the blade 13 rearward on its pivot. As its right-hand end portion is approached the blade 13 is inclined forward at a slight angle to the body portion, as indicated at 18, and at the end of this inclined portion bends forward sharply at nearly right angles as indicated at 19, passing through the slot 20 in the slotted bar 14, thence bending sharply to the right forward of the slotted bar, as indicated at 21. The right-hand end of the portion 21 has secured to it a forwardly projecting finger piece or handle 22 by which the blade 13 may be conveniently manipulated. The right-hand end of the slot 20 terminates to the left of the finger piece 22, and the face of the bar 14 to the right of this slot provides a stop for coöperation with the portion 21 to limit the rearward swing of the blade 13 under the action of its spring 17 and to determine the normal position of said blade. The slotted bar 14 is vertically disposed forward of the cutting blade and so as to leave a passage-way or opening 23 between them through which the paper or work sheet 9 passes. In its passage the paper extends close to the rear face of the bar 14. The bar 14 may be provided at its top and bottom edges with forwardly inclined horizontal lips or ledges 24, this construction being preferable as it promotes rigidity. The slot 20 is about midway between the lips 24 and is slightly wider than the thickness of the blade 13 and so that said blade 13 may be swung freely back and forth through it. The right-hand end of the bar 14 is provided with a forwardly extending horizontal ear 25 which receives a headed pivot screw 26, the said screw being secured in the right-hand end plate 11 and providing a support on which the bar is loosely pivoted at its right-hand end, the construction enabling the bar to be swung up to some extent about its pivot. At its opposite or left-hand end the bar 14 is provided with a finger piece 27 which is inclined slightly rearward from the body portion of the bar. Just to the right of this finger piece the bar fits into or engages in a holding notch or slot 28 formed vertically in the left-hand end plate 11. Secured to the front face of the bar 14 near its left-hand end as by rivets 29 is a detent device or spring finger or plate 30 which extends lengthwise of the bar and may be shaped at its free end into a finger piece 31 as shown. As shown, the plate is cut or kerfed at its right-hand end in register with the slot 20. The tendency of this plate 30 is to swing forward away from the face of the bar and it is provided with a rounded lug 32 which is normally maintained by this tension or tendency in engagement with a hole or opening 33 formed in the front wall of the slot 28 or the notch 28. The construction is such

that the re-action of the spring plate presses the bar 14 back against the rear wall of the notch 28, and said bar is locked or held normally in a predetermined position in relationship to the notch by the engagement of the lug 32 with the hole 33. By grasping and pressing the finger pieces 27 and 31 the lug is freed from the hole 33 so that the left end of the bar 14 may be swung up out of the notch and then the bar may be swung forward on its pivot 26 to a position such as that indicated by the dotted lines in Fig. 2 or even farther if desired. This forward swinging movement of the bar does not materially affect the blade 13 which remains substantially in normal position, and the construction enables the work sheet to be readily arranged between the bar and the blade or to be withdrawn, if desired. During the cutting or paper severing operations, however, the bar remains in normal position, being retained therein by the detent devices, the severing operation being performed by drawing the blade 13 forward through the slot 20, the blade being swung on its pivot to some such position as that illustrated by the dotted lines in Fig. 2. The forward or cutting edge of the blade need not be sharpened but may be substantially of the thickness of the body of the blade. The construction is such that the paper is sheared by the co-action between the forward edge of the blade and the edges of the slot or opening 20. The edge of the inclined portion 18 is first brought into co-operation with the right-hand edge of the paper and, after pressing the paper against the rear face of the bar, gives an easy start to the cutting operation which, it is apparent, will be a shearing one and is found in practice to give a clean and even cut and not an irregular tear as sometimes happens where the success of the cutting depends on the sharpness of the blade and where such blade has become dulled from use. The shearing operation in the present case is facilitated by the fact that the paper is held at opposite sides of the coöoperating cutting element; in other words, the paper is held or retained above the cutting elements by the roller 19 and below said elements by the rollers 8 and 7 in coöperation with the platen or section 5.

The rear upright face of the bar 14 provides in effect two strip portions whose surfaces are in the same plane but separated by a space or slot 20, the paper extending parallel with these surfaces and being pressed thereagainst at opposite sides of the space or opening by the severing blade while the paper is being cut.

My improved severing device is simple and inexpensive and at the same time has been found in practice to be highly efficient in operation.

Various changes may be made without departing from my invention.

What I claim as new and desire to secure by Letters Patent, is:—

70 1. A severing device for typewriting machines comprising a slotted bar, a cutting blade engaging the walls or edges of the slot in said bar, the slot in said bar extending completely through it transversely, and 75 means for affording relative transverse movement between said bar and said blade to shear the paper, the cutting edge of said blade being brought as a result of such relative transverse movement to the opposite 80 side of said bar from that normally occupied by it.

2. A severing device for typewriting machines comprising a slotted bar, a cutting blade engaging the walls or edges of the 85 slot in said bar, the slot in said bar extending completely through it transversely, said cutting blade being movably mounted and provided with a finger piece for moving the 90 blade to coöperate with said bar to shear the paper, said blade moving transversely through the slot in said bar from one side to the other.

3. A severing device for typewriting machines comprising a slotted bar, and a cutting blade engaging the walls or edges of the 95 slot in said bar, the slot in said bar extending completely through it transversely, said cutting blade being pivoted at one end and being provided with a finger piece at 100 the opposite end for swinging the blade on its pivot transversely through said slot from one side to the other.

4. A severing device for typewriting machines comprising a slotted bar, and a pivotally mounted cutting blade engaging the walls or edges of the slot in said bar and normally arranged to provide a passageway for the paper between it and the bar, said 105 blade being swingable on its pivot transversely through said slot from one side of the bar to the other to shear the paper.

5. A severing device for typewriting machines comprising a slotted bar, a cutting blade engaging the walls or edges of the slot 115 in said bar, the slot in said bar extending completely through it transversely, said cutting blade being mounted to move transversely of said bar to shear paper, said blade moving transversely through the slot 120 in said bar from one side to the other, and a restoring spring connected to said blade.

6. A severing device for typewriting machines comprising a slotted bar and a cutting blade engaging the walls or edges of 125 the slot in said bar, said blade and said bar being each pivotally mounted, the pivots being at opposite ends from each other.

7. A severing device for typewriting machines comprising a slotted bar and a cutting blade engaging the walls or edges of 130

the slot in said bar, said blade and said bar being each pivotally mounted, the pivots being at opposite ends from each other, said bar being provided at the end opposite from its pivot with devices for holding it against 70 movement.

8. A severing device for typewriting machines comprising a slotted bar and a cutting blade engaging the walls or edges of the slot in said bar, said blade and said bar 75 being each pivotally mounted, the pivots being at opposite ends from each other, said bar being provided at the end opposite from its pivot with devices for holding it against movement and said blade being provided 80 with a finger piece for moving it transversely of the slot in said bar.

9. A severing device for typewriting machines comprising a slotted bar, a cutting blade engaging the walls or edges of the slot 85 in said bar, said blade and said bar being each pivotally mounted, the pivots being at opposite ends from each other, said bar being provided at the end opposite from its pivot with devices for holding it against 90 movement and said blade being provided with a finger piece for moving it transversely of the slot in said bar, and a restoring spring for said blade.

10. A severing device for typewriting machines comprising a slotted bar, a cutting blade engaging the walls or edges of the slot 95 in said bar, the two parts being so arranged that normally there is a passage-way or opening between them for the paper, means 100 for affording relative movement between said bar and said blade to shear the paper, and means for affording another and different relative movement between the bar and the blade to facilitate the insertion of the 105 paper into the space between them.

11. A severing device for typewriting machines comprising a slotted bar, a movable blade having a cutting edge parallel for the greater part of its length with one face of 110 the bar, said blade engaging the walls or edges of the slot in said bar and being arranged so that normally there is a space between said bar and said blade for the paper, said blade being pivoted at one end 115 and its cutting edge near the opposite end being inclined toward the face of said bar, and adapted to pass transversely through said slot from one side of the bar to the opposite side, said blade being provided 120 with a finger piece which is normally at the side of said bar opposite to said space.

12. A severing device for typewriting machines comprising two coöoperating members pivoted at opposite ends from each other 125 and normally disposed so that there is a passage-way or opening for the paper between them, one of said members being movable on its pivot to sever the paper and the other of said members being movable on its 130

pivot to open said passage-way to facilitate the introduction of the paper into said passage-way and its withdrawal therefrom.

13. In a typewriting machine, the combination of a severing device comprising a pivoted plate or bar and a coöperating cutting blade, and a member provided with a recess or notch, the paper being arranged to pass normally between said blade and said bar and said bar being engageable at the end opposite from its pivot with said notch.

14. In a typewriting machine, the combination of a platen carrier, a platen, a cutting blade, a coöperative slotted bar, said blade and said bar being mounted for relative movement on said platen carrier, and

means at opposite sides of said blade and bar for holding a work sheet, said work sheet passing over the platen and between said blade and bar and being adapted to be cut ²⁰ by a shearing cut through the coöperation of said blade and bar, the blade moving transversely through said bar from one side to the other to effect such shearing cut.

Signed at the borough of Manhattan, city ²⁵ of New York, in the county of New York, and State of New York, this 17th day of January, A. D. 1913.

ARTHUR W. SMITH.
